UNITED STATES PATENT OFFICE

151,570

DESIGN FOR A PALATE PLATE BRUSH

Robert Frederick Taylor, Hounslow, England, assignor to G. B. Kent & Sons, Limited, London, England

Application July 18, 1947, Serial No. 140,375
In Great Britain March 11, 1946

Section 1, Public Law 690, August 8, 1946

Term of patent 14 years

(Cl. D9—2)

To all whom it may concern:

Be it known that I, Robert Frederick Taylor, a subject of the King of Great Britain, residing at Hounslow, England, have invented a new, original, and ornamental Design for a Palate Plate Brush, of which the following is a specification, reference being had to the accompanying drawings, forming a part thereof.

Fig. 1 is a bottom plan view of a palate plate brush, showing my new design;

Fig. 2 is a side elevation thereof; and

Fig. 3 is a front end view thereof.

I claim:

The ornamental design for a palate plate brush, substantially as shown.

ROBERT FREDERICK TAYLOR.
